UNITED STATES PATENT OFFICE.

FRANK S. SHANKLAND, OF DES MOINES, IOWA.

DESIGN FOR A BADGE OR EMBLEM.

57,545.

Specification for Design.

Patented Apr. 12, 1921.

Application filed October 14, 1920. Serial No. 417,060. Term of patent 7 years.

To all whom it may concern:

Be it known that I, FRANK S. SHANKLAND, a citizen of the United States of America, residing at Des Moines, in the county of Polk and State of Iowa, have invented a new, original, and ornamental Design for a Badge or Emblem, of which the following is a specification, reference being had to the accompanying drawing, forming part thereof.

I claim:

The ornamental design for a badge or emblem, as shown.

FRANK S. SHANKLAND.
